UNITED STATES PATENT OFFICE.

HENRY MOECKER, JR., AND THEODORE THOMPSON, OF HARVEY, ILLINOIS, ASSIGNEES
TO AMERICAN STOVE COMPANY, OF ST. LOUIS, MISSOURI, A CORPORATION OF NEW
JERSEY.

DOOR CONSTRUCTION.

Application filed December 27, 1921. Serial No. 524,976.

To all whom it may concern:

Be it known that we, HENRY MOECKER, Jr., and THEODORE THOMPSON, citizens of the United States, residing at Harvey, in the 5 county of Cook and State of Illinois, have invented certain new and useful Improvements in Door Constructions, of which the following is a specification, reference being had therein to the accompanying drawing.

10. Our invention relates to improvements in door constructions and more particularly to a construction for doors for warming ovens or the like which are provided in connection with gas or coal ranges for domestic use.

Our invention also relates to an improved door construction whereby the raising and lowering of the same is facilitated.

The primary object of our invention is 20 to provide a door with a hanger and pivot on which the door swings and a counter-weight for balancing the door.

Another object of our invention is to provide a swinging door for ovens or the like 25 which will swing up or down and is free from binding or sticking, as is likely with doors of other constructions.

A further object of our invention is to provide a door for ovens or the like which 30 can be raised to a position to leave completely unobstructed the door frame opening to allow free access to the interior of the oven.

Another object of our invention is to provide a door which is simple of operation 35 and protects the operator from possible burns sustained in handling a heated part of the oven or oven door.

A still further object of our invention 40 is to provide an oven door which is cheap and simple of manufacture and efficient in operation.

Our invention further consists in the novel construction, combination and arrangement 45 of parts, as will be hereinafter more specifically described and pointed out in the following specification, claims and accompanying drawings.

In the drawings:

50. Fig. 1 is a front elevation of a warming oven provided with my improved door construction, the door being shown in closed position.

Fig. 2 is an end elevation of a warming oven provided with a door of my improved

construction, the door being shown in closed 55 position.

Fig. 3 is an end elevation of a warming oven provided with my door of improved construction, the door being shown in open 60 position.

Fig. 4 is a detail perspective view of my improved door construction and its component parts.

Referring now to the drawings in which like parts are designated by similar reference numerals throughout the description and wherein we have shown a simple application of our invention, A represents a warming oven which may be of any desired shape or size and may be built as a 65 complete unit as shown in the drawings, or can be built into a gas or coal range as part of the range as is often the case.

The warming oven shown in the drawings is a complete unit comprising sides 1, 75 bottom 2, top 3, and front 4. A bead 5 extends around the sides and across the front of the oven about midway between its top and bottom. Above the bead 5 in the front 4 of the oven is an opening 6 which provides access into the interior of the oven. This opening 6 is approximately the same size as the front 4 of the oven above the bead 5, being surrounded on its sides and top by a small portion 4' of the oven front 80 4 and on its bottom by the bead 5.

This opening 6 is normally closed by a door 7 having inwardly extending flange portions 8 to which are suitably bolted or fastened at 9, rearwardly extending hangers 10 which carry on the inner side of the rear ends 11 counterweights 12. At a point which is in front of the counterweights 12 and on the outer side of the hangers 10 we have provided stub shafts 13 and 14. The 95 stub shaft 14 is provided with squared end 15 to which is attached a handle 16. As clearly appears in Fig. 4 of the drawings the hangers 10 of the door 7 are fastened to the inner side of the door flanges 9 and at a point midway between the door 7 and the stub shafts 13 and 15 the hangers are bent outwardly as at 17 so that that portion of the hangers in the rear of the bend 17 lies in a slightly different plane from their adjacent front hanger portions. The bend 17 in the hangers 10 is just sufficient in distance to make the flange portions 8 of the door lie in the same plane as the rear por- 100

105. tions.

tions of the hangers so that the width of the door 7 from flange to flange, outside measurement, is the same as the distance between the ends 11 of the hangers 10 of the 5 door.

In assembling the door 7 and its component in the oven A it will be seen that the door 7 is of a width and height to completely close the opening 6 in the oven front 10. 4. The stub shafts 13 and 15 extend outwardly through the oven sides 1 and the handle 16 is mounted upon the squared end 15 of the outwardly extending shaft 14. From the foregoing it will be readily understood that by rotating the handle 16 the door 7 is swung upon its shafts 13 and 14 and that unobstructed entrance to the oven A through the opening 6 is obtained, as the door 7 can be swung up to a position to lie 20 approximately beneath the oven top 3.

The door 7 will rotate very easily due to the counterweights 12, and after the door has been opened the same will remain in an open position, being held there by the 25 counterweights 12.

In those constructions of oven doors now prevalent the oven doors can not be opened completely to allow an unobstructed entrance to the oven interior, due to the fact that the 30 doors carry handles on their fronts which strike the oven top, which limits the movement of the door and the size of the opening into the oven.

With an oven door with a handle on its 35 front we have found that the handle becomes very hot and is liable to burn the hands of the operator while with the door handle or operating means of our improved construction the operator runs no risk of burning his hands when swinging the door to an open position.

Attention is also directed to the stub shaft 40 bearings 18 which bear against the inner sides of the oven sides 1 and hold the hangers 10 of the oven door just clear of the inner sides of the oven walls when the door is being swung. This construction assures that the door will swing easily and be free from binding or sticking as is very likely with 45 oven doors of other constructions.

Although we have shown the oven door 7 with the door as being flat it will be readily understood that our construction could be applied to an oven with a curved door without departing from the spirit of our invention. And we also wish it understood that we do not limit ourselves to the application of our construction to oven doors as our construction can be used in many other places 55 where swinging doors are desired.

Having thus described our invention, what we claim and desire to secure by Letters Patent is:

1. The combination with an oven or the like, of a swinging door with rearwardly extending edges, hangers for the door carried by said rearwardly extending edges, stub shafts carried by the hangers intermediate their ends, and means for rotating the door to open the same. 65 70

2. The combination with an oven or the like, of a swinging door with rearwardly extending edges, hangers for the door carried by the said door edges, and the end of the hangers adjacent the door in a different 75 plane from their other ends, for the purpose described.

3. The combination with an oven door or the like, of a swinging door, hangers for the door, outwardly extending stub shafts 80 carried by the hangers, counter weights carried upon the inner side of the hanger ends, and means to rotate one of the stub shafts, for the purpose described.

4. The combination with an oven door or the like, of a swinging door with rearwardly extending edges, hangers for the door carried upon the inner side of said door edges, and the ends of the hangers adjacent the door in a different plane from their other ends, for 90 the purpose described. 85

5. The combination with an oven or the like, of a swinging door provided with hangers, counter weights carried upon the inner 95 face of the hanger ends, outwardly extending stub shafts carried by the hangers at a point intermediate the door and the said weights, and one of the said stub shafts extending through the oven wall and provided with an operating handle, for the purpose 100 described. 100

6. The combination with an oven or the like, of a swinging door, hangers carried by the door, outwardly extending stub shafts carried by the outer face of the hangers intermediate their ends, one of said shafts extending outwardly beyond the oven side, and means to rotate the said outwardly protruding shaft, for the purpose described. 105 110

7. The combination with an oven or the like, of a swinging door provided with a hanger, the end of the hangers adjacent the door in a different plane from their other ends, outwardly extending stub shafts carried by the hangers, and means for rotating one of the stub shafts to open the door. 115

In testimony whereof we hereunto affix our signatures.

HENRY MOECKER, JR.
THEODORE THOMPSON.
